UNITED STATES PATENT OFFICE.

LEON WILLIAM SIMMONS, OF LOS ANGELES, CALIFORNIA.

FOUNTAIN MARKING-BRUSH.

1,393,841.

Specification of Letters Patent.

Patented Oct. 18, 1921.

Application filed May 26, 1920. Serial No. 384,375.

To all whom it may concern:

Be it known that I, LEON W. SIMMONS, a citizen of the United States, residing at Los Angeles, in the county of Los Angeles and State of California, have invented certain new and useful Improvements in Fountain Marking-Brushes, of which the following is a specification.

My invention relates to fountain marking brushes for use in sign painting, card writing, marking by stenciling and the like.

An important object of my invention is the provision of a fountain marking brush which can be readily filled and operated without the detachment of any of the parts.

A further object of my invention is the provision of a brush embodying means for carrying a marking fluid in the structure of the brush itself, thus doing away with inconveniences incident to the carrying of a separate container for the marking fluid.

A further object is the provision of a fountain brush embodying means for regulating a uniform and steady flow of the marking fluid to the brush element.

A further object is to provide a device as above described which will be inexpensive to manufacture; durable; efficient in operation; and exacting a minimum of wear upon any of its parts.

Other objects and advantages of the invention will be apparent during the course of the following description.

In the accompanying drawings, forming a part of this specification and in which like numerals are employed to designate like parts throughout the same.

Figure 1 is a side view or elevation of my invention.

Fig. 2 is a fragmentary vertical cross sectional view through my invention.

Fig. 3 is a bottom plan view of my invention showing the plunger element in an inoperable position.

Fig. 4 is a bottom plan view of my invention showing the plunger element in operable position.

Fig. 5 is a cross sectional view taken on the line 5—5 of Fig. 2.

Fig. 6 is a perspective view of the plunger element.

In the drawings, wherein for the purpose of illustration is shown a preferred embodiment of my invention, the letter A designates a tubular casing, adapted to act as a primary container for a marking fluid and having a brush receiving element or hollow cap B mounted upon an extremity thereof and acting as a secondary fluid container. A piston rod C, and piston or plunger element D are reciprocably mounted in the tubular casing A for the purpose of effecting the entrance of the liquid into the container and controlling the flow into the brush receiving element B.

The brush receiving element B is preferably formed in the shape of a hollow cap, being detachably connected by an upwardly extending annular flange 11^a to an extremity of the tubular casing A as by screw threads 11, and is preferably constructed in two sections, 12 and 13. Section 12 is the section detachably connected to the tubular casing and is provided with a passageway 14, forming means of communication between the tubular casing A and the opening 15 in the hollow cap B. Section 13 is hollow and preferably tapered, and is detachably connected to section 12 as by screw threads 16, the point of juncture of sections 12 and 13 being the point of greatest area of opening in the hollow tapering portion 13. The opposite or converging end of section 13 being provided internally with screw threads 18, adapted to receive an externally screw threaded plug 19.

The plug 19 is tapered to conform with the tapering of the hollow portion 13, a slot 20 being provided therein to receive a screw driver or other tool for readily seating the plug within the section 13. Bristles 21 depending from an end of the plug 19, and suitably mounted therein, have communication with the opening 15 of cap B, and the interior of the tubular casing A by means of slots 22 in the plug 19.

The piston rod C is reciprocably mounted within the tubular casing A, the upper ex-

tremity projecting from the tubular casing and being provided with a head 23. Screw threads 24 are provided upon the piston rod C immediately adjacent the head 23 and adapted for engagement with a screw threaded aperture 25 in a cap 26, the cap 26 being detachably connected to an extremity of the tubular casing A as by screw threads 27. The lower extremity of the piston rod C 10 or that portion depending within the tubular casing A is provided with a conical enlarged head 29, adapted to seat within the passageway 14 of the hollow cap B to regulate communication between the tubular casing A and the hollow cap B, upon rotation of the piston rod threads 24, within the screw threaded aperture 25. The conical head 29 is provided with a pin 30, laterally projecting therethrough and terminating 20 short of the internal walls of the casing A.

The piston D is preferably constructed of resilient or flexible material, and is provided with hooked pins 32 detachably connected thereto as by nuts 33, the projecting portions 25 of the hooks 32 being so arranged and depended from the piston D as to be readily engaged and disengaged by the pin 30. Because of the flexibility of the piston D, washers 35 and projecting portions 36 30 upon the pins 32 are provided to form a more effective construction. In operation it is obvious that as the screw threaded portion 24 of the piston rod is disengaged from the screw threaded aperture 25 the piston rod will be free to reciprocate within the tubular casing A; and independent of the reciprocation of the piston D. However as the piston rod is drawn upward till the conical head 29 fits within a depression 37 in 40 the piston, and the piston rod is rotated, the laterally projecting pin 30 will strike the hooked pins 32, and upon downward or a reciprocatory movement the piston will be reciprocated in unison with the piston rod, by means of the lateral pin 30 engaging the projections 34 of the hooked pins 32. In filling the tubular casing A with a marking fluid the hollow cap B is inserted into the fluid, the piston D is then drawn from the 50 bottom to the top extremity of the casing and the suction thus created within the casing will draw the fluid through the slots 22 into the casing A. Should the fluid be of such consistency as to require regulation of flow upon the brush, or it be desired to use only a limited amount, that amount can be regulated by means of rotating the screw threaded portion 24 of the piston rod C in the aperture 25, this operation having the 55 effect of regulating communication between the tubular casing 10 and the hollow cap 11.

It is to be understood that the form of my invention herewith shown and described is to be taken as a preferred example of the 60 same, for it may be desired to do away with

the regulation secured by the conical head 29 seating within the passage way 14, and have the marking fluid feed directly upon the bristles 21. Various other changes in the shape, size and arrangement of parts 70 may be desired and resorted to without departing from the spirit of my invention or the scope of the subjoined claims.

I claim:

1. In a fountain marking brush the combination of a tubular casing, a brush, a piston reciprocatingly mounted within said casing, a piston rod reciprocatingly carried by said casing, and means detachably connecting said piston and piston rod whereby 75 the latter may be reciprocated independently of the former.

2. As an article of manufacture, a hollow cap comprising an upper section provided with an upwardly extending annular flange 85 internally screw threaded, and a hollow tapering section detachably connected to said upper section, said hollow tapering section being internally screw threaded, and an externally screw threaded tapering plug adapted to engage the internally threaded hollow tapering section, said tapering plug having bristles attached thereon, and passageways therein providing a means of communication between the interior of the hollow cap 90 and the bristles.

3. In a fountain brush, the combination of a tubular casing, bristles carried by said tubular casing, having communication with the interior of the tubular casing, a piston reciprocatingly mounted within the tubular casing, a piston rod reciprocatingly carried by said casing adapted to regulate communication between the bristles and interior of the casing, and means carried by said piston and piston rod whereby they can be reciprocated in unison or the piston rod reciprocated independent of the piston. 100

4. In a fountain brush, the combination of a tubular casing, bristles mounted upon 110 said casing and adapted to receive liquid therefrom, a piston reciprocatingly mounted in said casing, hook pins mounted upon said piston, a piston rod reciprocatingly mounted in said casing, and pin extensions carried by and projecting laterally of said piston rod, whereby said piston rod can be rotated to engage the hooked pins and reciprocate the piston with the piston rod. 115

5. In a fountain brush, the combination 120 of a tubular casing; a piston comprising a disk like compressible body portion and washers at the opposite faces thereof; hooks carried by said piston and including stems extending through said washers and disk 125 like body; nuts in screw threaded engagement with the stems of said hooks adapted to compress the disk like body between said washers and into engagement with the wall of said tubular casing; and a piston rod 130

reciprocatingly mounted within the tubular casing having projections thereon to detachably engage the hooks of said piston for reciprocating the piston.

5 6. In a fountain brush, the combination, of a casing including primary and secondary chambers, a brush element in said secondary chamber, a piston and piston rod recipro-

cably mounted in said primary chamber, means detachably connecting said piston and piston rod whereby the latter may be reciprocated independent of the former, and a valve on said piston rod for regulating communication between said primary and secondary chambers.

LEON WM. SIMMONS.
